(57) CLAIM

The ornamental design for a package with surface ornamentation, as shown and described.

DESCRIPTION

FIG. 1 is a front plan view of the package with surface ornamentation showing a first embodiment of my new design;

FIG. 2 is a front plan view of a second embodiment thereof; and,

FIG. 3 is a front plan view of a third embodiment thereof. Any broken lines in the drawings indicate portions that form no part of the claimed design.
